UNITED STATES PATENT OFFICE.

RALPH ROSENBAUM, OF ATLANTA, GEORGIA.

BROOM.

No. 852,244.

Specification of Letters Patent.

Patented April 30, 1907.

Application filed August 16, 1906. Serial No. 330,885.

To all whom it may concern:

Be it known that I, RALPH ROSENBAUM, a citizen of the United States, residing at Atlanta, in the county of Fulton and State of Georgia, have invented certain new and useful Improvements in Brooms; and I do declare the following to be a full, clear, and exact description of the invention, such as will enable others skilled in the art to which it applies to make and use the same.

This invention relates to improvements in brooms.

The object of the invention is to provide a broom having arranged on the upper end of its head a shield or cap and on its side edges guard plates by means of which the upper edges of the broom head are protected from abrasion or wearing by coming into contact with obstructions having rough surfaces.

A further object is to provide an improved means for securing the edge protecting plates on the broom head.

With the above and other objects in view, the invention consists of certain novel features of construction, combination and arrangement of parts, as will be hereinafter described and claimed.

In the accompanying drawings:—Figure 1 is a broken perspective view of a broom constructed in accordance with the invention; Fig. 2 is a horizontal sectional view taken on a line with one of the shield and handle fastening devices; and Fig. 3 is a similar view taken through the side protecting or guard plates on a line with one of the rows of stitching for securing said plates to the broom head.

Referring more particularly to the drawings, 1 denotes the broom head, to which is secured the handle 2. On the upper end of the broom head 1 is arranged a cap or shield 3, which is preferably formed of a sheet metal strip or band bent around the upper end of the broom head, the ends of said shield plate being slipped over each other to a suitable distance, as shown.

Through the shield and the upper end of the broom head is inserted two or more fastening devices 4, said devices being here shown and are preferably in the form of staples, the ends of which, after being passed through one side of the shield and the broom head are passed through the lapped ends of the opposite side of the shield, after which said ends are bent at right angles and again forced through the lapped ends of the shield

and into the lower end of the broom handle, thereby serving the double function of fastening the shield onto the head of the broom and also securing the handle in said head. 60

On the sides of the upper portion of the broom head are arranged curved guard plates 5, the upper ends of which are inserted beneath the lower edge of the shield 3 and held in place thereby. The guards are 65 loosely secured at their upper ends under the cap 3 and are therefore preferably made of a substantially uniform width throughout their lengths for the purpose of securing a sufficiently rigid fastening without the necessity of rigidly connecting the upper ends with the cap. In the lower end of the guard plates 5 adjacent to each edge are formed a series of perforations 6, through which and the head of the broom is adapted to be passed 70 the end cross threads 7, with which the broom is stitched. The cross threads 7 are looped around the binding or horizontal threads 8 of the broom in the usual manner, said binding threads being passed around the outer side of 75 the guard plates, thereby securely fastening the same to the edges of the broom head. By thus fastening the guard plates, the same are secured simultaneously with the stitching of the broom head, said threads serving the 80 two-fold purpose of holding the broom head together and the guard plates in place. It also avoids the placing of any of the threads in straining or drawing contact with the sharp edges of the perforations 6, as the 85 threads 8 pass over said holes and the threads 7 through them, whereby the strain or contact of the threads 8 is upon the smooth outer faces of the plates 5, and the strain or contact of the threads 7 is upon the threads 8. 90

By providing a shield or cap on the upper end of the broom head and guard plates on the edges thereof to extend below the lower end of said shield, the broom straws will be 95 fully protected at such points where the same is liable to be worn or broken out contact with obstructions in sweeping thereby greatly prolonging the life and usefulness of the broom.

From the foregoing description, taken in 105 connection with the accompanying drawings, the construction and operation of the invention will be readily understood without requiring a more extended explanation.

Various changes in the form, proportion 110 and the minor details of construction may be resorted to without departing from the prin-

inciple or sacrificing any of the advantages of this invention, as defined by the appended claim.

Having thus described my invention, what I claim as new and desire to secure by Letters-Patent, is:—

In a broom, a cap on the head thereof, a curved guard plate on each side of the broom, the upper end of which is removably seated under said cap and the lower end is perforated upon each edge, binding threads around the head and around the lower ends of said plates, said threads passing over said perfora-

tions, and cross threads through the head and through said perforations and around the binding threads, whereby the straining contact of the threads with sharp edges is avoided.

In testimony whereof I have hereunto set my hand in presence of two subscribing witnesses.

RALPH ROSENBAUM.
